(57) **CLAIM**

We claim the ornamental design for a case for an electronic device, as shown and described.

DESCRIPTION

FIG. 1 is a rear view of the case for an electronic device in accordance with a first embodiment of the invention;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a rear left perspective view thereof;

FIG. 8 is a partial enlarged view thereof, taken from the encircled portion 8 in FIG. 1;

FIG. 9 is a partial enlarged view thereof, taken from the encircled portion 9 in FIG. 7;

FIG. 10 is a front right perspective view thereof;

FIG. 11 is a sectional view of the case taken along line 11-11 in FIG. 3;

FIG. 12 is a rear view of a case for an electronic device in accordance with a second embodiment of the invention;

FIG. 13 is a front view thereof;

FIG. 14 is a left side view thereof;

FIG. 15 is a right side view thereof;

FIG. 16 is a top view thereof;

FIG. 17 is a bottom view thereof;

FIG. 18 is a rear left perspective view thereof;

FIG. 19 is a partial enlarged view thereof, taken from the encircled portion 19 in FIG. 12;

FIG. 20 is a partial enlarged view thereof, taken from the encircled portion 20 in FIG. 18; and,

FIG. 21 is a front right perspective view thereof.

The broken lines depicting portions of the case for an electronic device form no part of the claimed design. The broke line circles found in FIGS. 1, 7, 10 and 16, are for the purpose of disclosing the partial enlarged views of respective FIGS. 8, 9, 19, and 20, and form no part of the claimed design.
